Primary Examiner — Ryan Harvey(74) *Attorney, Agent, or Firm* — Wood Herron & Evans LLP(57) **CLAIM**

The ornamental design for an exercise platform, as shown and described.

DESCRIPTION

FIG. 1 is a front right perspective view of an exercise platform according to the present invention.

FIG. 2 is a rear left perspective view of the exercise machine shown in FIG. 1.

FIG. 3 is a front view thereof.

FIG. 4 is a rear view thereof.

FIG. 5 is a left side view thereof.

FIG. 6 is a right side view thereof; and,

FIG. 7 is a top view thereof.

The broken line showing of portions of the exercise platform depicts environment and forms no part of the claim.
